CHESTER K. BROOKS, OF CLEVELAND, OHIO, ASSIGNOR TO THE NATIONAL MALLEABLE CASTINGS COMPANY, OF CLEVELAND, OHIO, A CORPORATION OF OHIO.

FRICITION DRAFT-RIGGING.

1,121,970.

Specification of Letters Patent. Patented Dec. 22, 1914.

Application filed September 11, 1909. Serial No. 517,303.

To all whom it may concern:

Be it known that I, CHESTER K. BROOKS, a citizen of the United States, and a resident of Cleveland, Cuyahoga county, Ohio, have ⁵ invented a new and useful Friction Draft-Rigging, of which the following is a full, clear, and exact description, reference being had to the accompanying drawings, forming part of this specification, in which—

10 Figures 1 and 2 are horizontal longitudinal sections of a draft rigging embodying my invention, with the parts shown in different position in the two figures.

15 My invention has relation to friction draft rigging of the type which employs toggle actuated friction members, and is designed to provide means for maintaining a substantially constant angle of inclination of the toggles notwithstanding wear of the parts, ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰

20 whereby the capacity of the rigging remains substantially constant.

A further object of the invention is to so arrange the toggles and toggle actuating members so that the initial shock either of ²⁵ pulling or buffing cannot be transmitted directly through the toggle plates and toggles in a manner to cause either the splitting of the friction casing or the sticking of the friction members.

20 The nature of my invention will be best understood by reference to the accompanying drawings in which I have shown a preferred embodiment thereof, and which will now be described, it being premised, however, ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰

that various changes may be made in the details of construction and arrangement of the various parts by those skilled in the art without departing from the spirit and scope of my invention, as defined in the appended claims.

In these drawings, the numeral 2 designates the draft sills between which is mounted a longitudinally movable casing 3. This casing is held from rearward movement by ⁴⁵ means of draft lugs 4 which are riveted or otherwise rigidly secured to the draft sills 2.

50 5 is the yoke which is secured to the coupler shank 6, and which incloses the draft rigging.

55 7 is a filler block which is inserted between the rear end of the casing 3 and the rear portion of the yoke and which forms the bearing for the filler block against the rear end of the casing. The rear end of the coupler shank 6 bears against a follower 8, which is

seated between the friction members of the draft rigging hereinafter described and the forward draft lugs 9, which are secured to the draft sills 2. The provision of the follower block 7 permits the use of a rounded ⁶⁰ yoke.

The arrangement of the parts thus far described, is not essential to my invention, but illustrate satisfactory means for use in connection therewith.

10 designates friction plates or members, which have frictional contact with the inner surface of the casing 3, the coating surfaces of said plates and of the casing walls being slightly converging toward the rear, so that ⁷⁰ when the friction plates are caused to enter the casing, they are also forced by the converging walls thereof to approach the center line of the draft rigging.

11 designates toggle actuating plates, between which and the friction plates 10 are interposed the toggle members 12, said toggle members having rounded or convexed ends which engage in cavities or recesses 12^a in the inner faces of the plates. The friction plates 10 bear at their forward ends on the rear face of the follower 8, and the toggles are adapted to transfer pressure from the draw bar or the yoke outwardly upon the friction plates, thereby causing frictional contact between said plates and the walls of the casing in the manner to be hereinafter described.

A wedge 13 is interposed between the two toggle actuating members 11 from the rear, said wedge being always held under slight pressure by means of a wear adjusting spring 14. This spring is seated between the wedge and the inner face of the rear end of the casing. This wedge and spring serve to take up any wear that may occur, and which if not compensated for, would cause a change in the angle of inclination of the toggles. This would mean an increase in the outward pressure exerted and would cause the toggles to gradually approach so

nearly a perpendicular position that a tremendous spreading force would exist tending to rupture the casing. Between an abutment 11^a on the toggle actuating members 11 and the forward abutment 10^a on the friction plate 10 is seated a short spring 15. The function of this spring is to permit of relative movement of the friction plates 10 and the toggle actuating plates 11 under

buffing and pulling strains and yet oppose the force of the wear spring 14 in order to maintain a fixed relation between the friction plates and the toggle actuating plates 5 in a longitudinal direction, when the parts are in normal positions. This prevents the pressure of the wear spring from acting to force the toggle actuating plates forwardly and consequently cause too great an angle 10 of inclination of the toggles. In the normal position of the parts, that is to say, when they are under neither buffing or pulling strains, as shown in Fig. 1, the free length of the spring 15 is such that the toggle actuating members are just in contact with the follower 8; but this contact is so slight that they receive no initial blow or pressure from the follower due to a buffing or pulling force. This blow, when a pulling 20 or buffing shock takes place, is transmitted through a release spring 16 to the friction plates 10. For clearness, we shall first consider the action of the draft rigging under a buffing force only, in which case the casing 3 remains immovable against the rear lugs 4 and all motion of the parts causing them to enter the casing will be spoken of as inward movement and motion in the opposite direction as outward movement.

30 The novelty in the device consists in providing means, viz., the toggles 12 in combination with the inwardly converging walls of the casing 3, whereby the friction plates 10 are caused to move inwardly at a more rapid rate than the follower 8 and the toggle plates 11. When buffing pressure is applied to the follower 8, the tendency is to push the friction plates and the toggle plates inwardly and at the same rate, but, 40 due to the inwardly converging walls of the casing, the friction plates 10 are caused to move toward each other as they move inwardly, thus causing the toggles 12 to assume a position more nearly parallel to the longitudinal axis of the draft rigging. As the toggles rotate, they bear at one end on the toggle plates 11 and push the friction plates 10 inwardly at a relatively greater rate of speed, at the same time forcing the 45 friction plates 10 against the casing to produce the desired frictional resistance. In other words, although both the toggle plates and the friction plates travel inwardly under a buffing force, the friction plates have an inward movement relative to the toggle plates 11, since the latter are caused to move more rapidly inwardly by the partial rotation of the toggles within their sockets. This means that during the 55 inward motion, the friction plates move away from their contact with the moving follower 8 by reason of their more rapid movement, thereby leaving the toggle plate 11 to receive the pressure from said follower, 60 which is the desirable end to be secured. It

should be clearly understood, however, that the device operates in the same manner under a pulling force, except that the casing itself moves forwardly (with relation to the car) while the toggle plates 11 remain stationary in contact with the front follower. The movement of the casing and other frictional parts with relation to each other is precisely the same whether in buffing or pulling. When under a pulling strain, the 70 casing 3 is moved forwardly over the friction devices, and the friction plates 10 are moved rearwardly into the casing, so that all of the pulling strain is transmitted to the follower 8 through the medium of the 75 toggle plates 11, as clearly shown in Fig. 2 of the drawing. When the buffing or pulling force has ceased, the only pressure upon the inner ends of the toggles is that which is caused by the very slight compression of 80 the spring 15. The friction between the walls of the casing and the friction plates is then so far reduced that the release spring 16 is able to return the friction plates at once to their normal positions, the wear 85 spring 14 following and maintaining the wedge in its same position with reference to the toggle actuating plates, and the short spring 15 rotating the inner ends of the toggles back to their initial position. Even 90 with the parts in normal position as shown in Fig. 1, this wear spring is under a considerable compression, so that as wear occurs the wedge is constantly pushed forward. The wear is thus taken up and any 95 change in the angle of the toggles is prevented.

The draft rigging described is simple in its construction and arrangement of parts; is capable of exerting a powerful frictional 100 action in operation; its capacity is maintained substantially constant by reason of the means which are provided as above described, for maintaining the angle of inclination of the toggles substantially constant notwithstanding wear of the friction surfaces; and initial shocks either of pulling or buffing are prevented from being transferred directly through the toggle plates and toggles. It is only after the friction 110 plates have begun to enter the casing and therefore to approach each other, that the toggles push the toggle plates forwardly, sufficiently to receive pressure from the follower.

115 It will be obvious that various changes may be made in the details of construction and arrangement of the several parts without departing from the spirit and scope of my invention. Thus the friction plates, the 120 toggle actuating plates, and the toggles, may be of different forms; instead of toggles, other means may be employed for actuating friction plates. Changes may be made in the arrangements of the wear compensating 125

wedge; and the manner of engaging the draft rigging with the yoke and coupler shank may also be changed.

I claim:

5 1. In frictional shock absorbing mechanism, a longitudinally-extending casing having an open end, a spring within the casing, and opposite friction faces which converge toward each other in a direction away from 10 said open end and toward the spring, friction members in contact with said friction faces, pressure-transmitting means adapted to press said friction members laterally against said friction faces and to move them 15 longitudinally relative to said friction faces under the compressive forces of buffing or draft, and a follower initially in contact with the friction members and with the pressure-transmitting means, said follower 20 being out of contact with the friction members after the beginning of the compressive movement.

2. In frictional shock absorbing mechanism, a casing having convergent friction faces, a front follower, friction blocks having only an initial engagement with the front follower and bearing against the friction faces of the casing, actuating members extending longitudinally between the friction blocks and having a bearing at all 30 times against the front follower, and a pressure member interposed between each actuating member and the adjacent friction block, the said pressure members being 35 adapted to transmit pressure from the actuating members to friction blocks.

3. In frictional shock absorbing mechanism, a casing having convergent friction faces, friction blocks having an outward bearing against said faces, actuating members, pressure members having a bearing on 40 the actuating members and being adapted to compress the friction blocks against the friction faces of the casing, and a compensating member between the actuating members.

4. In frictional shock absorbing mechanism, a casing having convergent friction faces, friction blocks having outward bearing against said faces, actuating members, pressure transmitting members having a bearing on the actuating members and the friction blocks, and a compensating device 50

coöperating with the actuating member for maintaining the pressure transmitting members in their initial position at a constant inclination with regard to the friction blocks and the actuating members irrespective of the wear of the parts.

5. In frictional shock absorbing mechanism, a casing having convergent frictional surfaces, friction blocks in contact with said surfaces, inclined toggle members in contact with said friction blocks, toggle actuating means in contact with said toggle members, 60 and wedge means engaging said toggle actuating members for maintaining the toggles at a constant angle of inclination while in their initial position, irrespective of wear of the parts.

6. In a friction draft rigging, friction members, toggle - actuating members, obliquely placed toggles interposed between the friction members and the toggle-actuating members, and a spring-pressed compensating wedge between the toggle-actuating members.

7. In a friction draft rigging, a casing member, frictional members arranged to contact therewith, a follower in contact with the said friction members, toggle actuating members, toggles interposed between the toggle actuating members and the friction members, and a spring interposed between the friction members and the toggle actuating members.

8. In a friction draft rigging, a casing member, a plurality of friction members to contact with the casing member, a follower in initial contact with the friction members, a release spring seated between the friction members and the casing member, toggle actuating members also arranged to contact with the follower, toggles between the toggle actuating members and the friction members, a spring actuated wedge between the toggle actuating members, and a spring interposed between the toggle actuating members and the friction members.

In testimony whereof, I have hereunto set my hand.

CHESTER K. BROOKS.
